GEORGE C. BEIDLER, OF ROCHESTER, NEW YORK

APPARATUS FOR TREATING PHOTOGRAPHIC FILMS

Application filed February 21, 1927. Serial No. 169,994.

This invention relates to photography, and particularly to means for treating film that has been photographically exposed and is in process of development or other treatment.

It is an object of this invention to provide means for submerging and moving film, and the invention has especial reference to means for operating on films progressively as they reach certain stages of their treatment during the developing processes.

The commercial photographing and developing machines now in practical use have means for exposing film to light, usually associated with means for feeding the film from a roll into an exposing chamber, and after exposure, moving the film from the exposing chamber into a receptacle or film treating part of the apparatus, the exposed portion of the film being usually severed from that portion of the film in the exposing chamber. In types of these machines having the characteristics just stated, the film is developed within the photographing apparatus and after being developed is subjected to the action of fixing fluid while in said apparatus and without being transferred to an ordinary photographic dark room.

Films that have been photographed, developed and subjected to the fixing fluid in the apparatus of the commercial types now in use are usually transferred to a dark room for washing and the films are thereafter dried.

There are in commercial use, machines for washing and drying film, and an understanding of the foregoing will lead to an appreciation of the objects and advantages of this invention when it is stated that when film has been exposed and cut and then developed and delivered to a receptacle for subjecting the film to the action of fixing fluid successively, it is desirable that the said film should remain in the fixing fluid a predetermined time, depending upon the strength of the fixing solution. Under these conditions, a number of the films are in a receptacle containing the fixing solution and it is the object of this invention to re-

move the films, one at a time, from the fluid and eject it from the receptacle, from whence it may be taken to a washing and drying machine; and it is furthermore an object of this invention to produce novel means whereby the films which are superimposed in the fluid will be so ejected, one at a time, and without crumpling or creasing those films remaining in the fluid.

It is a further object of this invention to provide means for moving the film downwardly in the fluid in successive steps, during which movement the film is under treatment tending to fix the same, and means are provided for removing the lowermost of the films as it reaches a predetermined position with relation to the operating parts of the device.

It is a still further object of this invention to provide means for operating the film depressing device and the film drawing means step by step and in time with the delivery of film to the fixing fluid.

Applicant is the inventor of a film transfer disclosed in application for letters patent filed October 24, 1925, Serial No. 64,560, which moves film from a developing fluid to a receptacle containing fixing fluid and in the transfer mentioned, the film when delivered to the fixing fluid floats on the fixing fluid with a slight coating of the fixing fluid on its upper surface. In the delivery of the film to the fixing fluid, the film is caused to move over the surface of the fixing fluid away from the means for delivering it to the fixing fluid, and it is the purpose of the inventor to so station the apparatus of the present invention in the receptacle for the fixing fluid that the said film in its floating state will reach and come under the influence of the aforesaid means for depressing or moving the film downwardly in the fixing fluid, and preferably, the device of this invention will be stationed in a receptacle for fixing fluid at or near the end thereof opposite that occupied by a transfer which delivers film to the fixing fluid.

With these objects and the visual relation of the film delivery and the film re-

moving instrumentalities associated with a receptacle having fixing fluid, it may be stated that it is a further object of the invention to synchronize the operations of the film moving means in order that they will 5 operate in time to accomplish the foregoing results.

With the foregoing and other objects in view, the invention consists in the details of construction, and in the arrangement and 10 combination of parts to be hereinafter more fully set forth and claimed.

In describing the invention in detail, reference will be had to the accompanying drawings forming part of this application 15 wherein like characters denote corresponding parts in the several views, and in which—

Figure 1 illustrates a view in perspective 20 of a film moving and ejecting means embodying the invention;

Figure 2 illustrates a longitudinal sectional view of a receptacle showing a device embodying the invention in end elevation;

Figure 3 illustrates a longitudinal sectional view of the machine;

Figure 4 illustrates a front view thereof in elevation;

Figure 5 illustrates a plan view of fragments of the machine;

Figure 6 illustrates an enlarged sectional view on the line 6—6 of Fig. 4;

Figure 7 illustrates a perspective view of a power transfer control;

Figure 8 illustrates a detail view of an intermittently operating power transmitting means;

Figure 9 illustrates a sectional view on the line 9—9 of Fig. 8, with a tripping device in place; and

Figure 10 illustrates a detail view of certain parts of the gearing.

In these drawings, 15 denotes a receptacle for fluid, and in the preferred use, fixing fluid is in the receptacle, and the instrumentalities of the invention, excepting the drive therefor, are assembled on a frame which may be applied to or removed from the receptacle, although this embodiment includes only the preferred form of the invention as so far developed. End frame plates 16 and 17 are associated with a connection, here shown as an angle iron 18, which extends from one plate to another 45 and which is secured thereto in any approved way, to produce a rigid structure. Journal bearings 19 and 20 are secured to the element 18 and the shafts 21 and 22 are journaled in the respective bearings. The 50 shafts 21 and 22 are respectively provided with wheels 23 and 24, engaged by wheels 25 and 26, respectively on a shaft 27. The wheels 25 and 26 are set on opposite sides of the shafts 23 and 24 and rotate the shafts 55 in a clockwise and anti-clockwise direction,

respectively. A helical or screw conveying device 28 is located on the lower end of each shaft and in spaced relation to the bottom of the receptacle in which the apparatus is located.

A plurality of plates 29 is secured edge-wise at the bottom of the frame structure, and these plates have horizontally disposed edges 30 merging with edges that are upwardly inclined as at 31 so that the plates 70 75 constitute guides on which films are supported while traveling in their exit or discharge from the receptacle.

Shafts 32 and 33 are journaled transversely of the frame members and they extend through the vertically disposed plates 29. Rollers or sleeves 34 are applied to the shaft 33 between the plates and other rollers or sleeves 35 may be applied to the shaft 32. Conveyor belts or bands 36 may be provided in appropriate number for the purpose intended, but preferably at least one should be located under or approximately under a conveyer 28. The rollers on which the belts are applied may be slightly less in 80 85 diameter than the other rollers in order that the supporting surfaces of the belts and the peripheries of the other rollers will be on the same plane.

A shaft 37 is journaled transversely of the frame in a plane above the shaft 33 and friction wheels 38 thereon have peripheries which normally engage the rollers 34 immediately thereunder. Preferably the 90 wheels 38 have rubber faces 39 for increasing the friction on the film which is to be moved by them when rotated. It will be seen from an inspection of the drawing, and especially Fig. 3, that the wheel 38 operates at the junction of the horizontal and inclined surfaces of the plates 29 and they assist in drawing the film from the receptacle and forcing it up the inclined surfaces of the plates or guides. Wringing rollers 40 and 41 are journaled in operative relation to each 100 105 other in such location with respect to the guiding plates that they will receive film in its travel from the receptacle and press the fixing fluid therefrom in order that it may be delivered to a conveyer 42, conventionally shown, for transfer to a station where it may be further treated. Preferably, the inventor utilizes the conveyer for delivering the developed film to a washing and drying apparatus of known construction.

Power may be applied to the several movable parts described, but in order to produce synchronous action of the said device and the film pretreating instrumentalities, a shaft 43 of the roller 41 is provided with a 115 wheel 44 engaging a wheel 45 and the wheel 45 drives a wheel 46, which in turn drives a wheel 47. The shaft 48 of the roller 40 and the shaft 43 are geared together as at 49, and therefore, they rotate in unison when 120 125 130

- the shaft 43 is driven by power from any suitable source. The driven wheel 47 is on the shaft 27 and it is free to rotate thereon without communicating motion to the shaft, but provision is made for communicating its motion to the shaft intermittently. As a means for intermittently rotating the shaft 27, the wheel 47 has a sleeve 50 and the sleeve has a tooth or lug 51 on its periphery. 5
- 10 A disk 52 is secured on the shaft 27 and it has a pin 53 extending from its side toward the wheel 47. The pin 53 acts as a pivot for a dog 54 having a nose 55 adapted to engage the tooth 51, although it may be held out of engagement therewith when the arm or extension 56 of the dog comes in contact with a control rod 57. The control rod may be moved to release the dog, and when so released, it will engage the tooth 51 and cause the motion of the wheel 47 to be 15 communicated to the shaft 27 through the disk which is secured on the shaft 27. The operating rod 57 consists of an angularly disposed portion of a rod 58 which is partially rotatable in the frame structure, and an arm 59 thereon may be actuated by any suitable means for moving the rod with relation to the dog, with the result that the shaft 27 may be alternately driven and arrested. 20
- 25 The arm 59 may be controlled from a photographing and developing apparatus and made to operate each time a print is produced, for by this means, when developing instrumentalities are employed in connection with the photographing machine, a film can be delivered to the receptacle 15 at the top of the fluid, while another one which has remained in the fixing fluid during the cycles of operation necessary to transfer the film 30 from the top to approximately the bottom of the fluid in the receptacle, may be removed from the receptacle.
- 35 The wheel 45 is rotatable on a stub shaft 60 and the wheel 46 is secured on a shaft 61 journaled transversely of the frame. A wheel 62 is on the shaft 61 on the inner side of the plate or frame member 17 and it engages and drives a wheel 63 on the shaft 37, so that by this means, the friction wheels 38 40 are rotated. The peripheries of the friction wheels are in engagement with the rollers 34 that are secured on the shaft 33, and therefore, the friction wheels turn the shaft 33 and this serves to operate the conveyers or 45 belts 36 for removing film from the bottom of the receptacle as it is delivered to the conveyers during the successive operations of the screw conveyer.
- 50 The screw conveyer or submerger has a plurality of helically arranged film engaging plates or convolutions which are operative to receive the edges of films and move them downwardly in the fluid as rotary motion is imparted to the conveyer. The top 55 of each conveyer is provided with a flared
- mouth to facilitate the entrance of the film to the space between the uppermost lead of the conveyer and the one succeeding it, and from the fact that the conveyers are rotated in opposite directions and toward the sides 70 of the device, they will operate to maintain the film in a flat state.
- 75 From what has been stated of the functions of the elements as they have been described, it is believed unnecessary to present a résumé of the operation, but briefly it may be stated that film delivered to a receptacle containing fixing fluid would preferably have the fixing fluid on a level with the so-called mouths of the conveyers in order that so film floating on the fixing fluid would move into the zone of operation of the conveyers. The shaft 43 may be continuously or intermittently driven, and when driven, it will, through the gearing described, cause the operation of the friction wheels and they will rotate the shaft 32 and this in turn will operate the conveyer belts 36 for moving film discharged from the submerging conveyers to the means for discharging film from the 90 receptacle. Since it is desirable to have the film remain in the fixing fluid a predetermined time, provision is made for intermittently operating the submerging conveyers, and therefore, at each operation of the submerging conveyers, the films will be moved, step by step, downwardly in the fluid until they reach the lower ends of the submerging conveyers where they will be under the influence of the belt conveyers and ejected 95 from the receptacle.
- 100 It is shown in the drawing that the plates 29 are supported on their edges by a plate 64 having a rib 65 and the rib is channeled to form seats in which the plates are located.
- 105 The nose 55 of the dog is forced into engagement with the lug 51 by a spring 51^a when the rod 57 is operated to release the dog. In Fig. 9 the relation of parts is shown as they appear just prior to the tripping 110 of the dog through its coming in contact with the said arm 57, it being understood that if the wheel 47 is turned in the direction of the arrow, it will carry the extension 56 of the dog against the end of the rod 57 and disengage the nose of the dog from the said tooth, and therefore, the drive to the shaft 27 will be interrupted. If the rod 57 is swung downwardly past the extension 115 of the dog, the spring will again force the nose of the dog into engagement with the tooth and the shaft 27 will again be driven. If the rod 57 is swung downwardly past the extension 120 of the dog, the spring will again force the nose of the dog into engagement with the tooth and the shaft 27 will again be driven. By this means the shaft 27 is intermittently controlled.
- 125 I claim:
1. In a film treating apparatus, a receptacle for holding fluid, mechanical means therein for engaging successive films and moving them downwardly in the fluid, and

- means for successively removing each film when it reaches the lowermost position.
2. In a film treating apparatus, a receptacle for holding fluid, mechanical means associated therewith for receiving films and moving a plurality of films downwardly step by step, and means for successively removing each film when it reaches the lowermost position from the receptacle.
3. In a film treating apparatus, a receptacle for holding fluid, mechanical means for engaging portions of superimposed films in the fluid and moving them step by step downwardly in the fluid simultaneously, and means for successively removing each film when it reaches the lowermost position.
4. In a film treating apparatus, a receptacle for holding fluid, mechanical means associated with the receptacle and operative to engage the superimposed films when in horizontal positions in the fluid and move them step by step downwardly in the fluid simultaneously, and means for successively removing each film when it reaches the lowermost position.
5. In a film treating apparatus, a receptacle for holding fluid, helical film moving means to which the edges of films in the fluid are delivered, means for rotating the helical film moving means for moving the films downwardly in the fluid while in approximately horizontal positions, and means for removing the successive lowermost film from under the superimposed film.
6. In a film treating apparatus, a receptacle having fluid for receiving successive films flatwise on its surface, a device having means for receiving the edges of the films and operative to move the films downwardly in the fluid and releasing films successively, and means for removing the films from the receptacle as released by the said means.
7. In a film treating apparatus, a receptacle for holding fluid and to which films are delivered flatwise in said fluid, helical film moving means to which the edges of the films are delivered while in the fluid, means for rotating the helical film moving means whereby the films are forced downwardly in the fluid, and means for removing successive films from under those contained in the fluid.
8. In a film treating apparatus, a receptacle for holding fluid, mechanical means for engaging portions of superimposed films in the fluid and moving them step by step downwardly in the fluid simultaneously and freeing them successively, means for removing the freed film from the receptacle, and means for operating the last mentioned means in time with the freeing action of the said mechanical means.
9. In a film treating apparatus, a receptacle for holding fluid and to which films are delivered superimposed and flatwise,
- means for engaging films and holding them separated, means for moving the films successively downwardly in the fluid and successively releasing each film when it reaches the lowermost position, and means for removing the released films from the fluid.
10. In a film treating apparatus, a receptacle for holding fluid and to which films are delivered superimposed and flatwise, means for engaging films and holding them separated, means for moving the films successively downwardly in the fluid and successively releasing each film when it reaches the lowermost position, means for removing the released film from the fluid, and means for timing the action of the last mentioned means to the release of the successive films.
11. In a film treating apparatus, a receptacle for holding fluid, mechanical means for engaging portions of superimposed films in the fluid and moving them step by step downwardly in the fluid, means for moving the lowermost film from the fluid successively when it reaches the lowermost position, including means for displacing fluid from the film in its travel from the receptacle.
12. In a film treating apparatus, a receptacle for holding fluid, mechanical means in the receptacle comprising a frame, helical film engaging means, means for rotatably mounting the said engaging means with its axis approximately vertical, a conveyor under the engaging means for receiving films released thereby, and means for driving the helical film engaging means and the conveyor in time for removing films delivered by the helical film engaging means from the fluid.
13. In a film treating apparatus, a receptacle for holding fluid, mechanical means in the receptacle comprising a frame, a helical film engaging means, an approximately vertically disposed rotatable shaft on which the engaging means is secured, film discharging mechanism comprising a roller and friction wheels coacting therewith, means for delivering films under the helical film engaging means to the said roller, means for operating the helical film engaging means intermittently, and means for discharging moisture from the films in their exit from the receptacle.
14. In a film treating apparatus, a receptacle for holding fluid, mechanical means therein for engaging successive films and moving them downwardly in the fluid, means for intermittently operating the said mechanical means, and means for controlling the intermittent operation thereof.
15. In a film treating apparatus, means for progressively moving horizontally positioned superimposed films downwardly in a receptacle, and mechanical means coacting therewith for removing the lowermost of

said films from the receptacle when it reaches the lowermost position.

16. In a film treating apparatus, mechanical means for moving horizontally positioned films downwardly in a receptacle and releasing said films, and mechanical means coacting therewith for removing the released films from the receptacle.
